ATTORNEY.

UNITED STATES PATENT OFFICE.

NICK W. KLINE, OF LOS ANGELES, CALIFORNIA.

TRUSS.

1,357,405.

Specification of Letters Patent.

Patented Nov. 2, 1920.

Application filed February 4, 1919. Serial No. 274,971.

To all whom it may concern:

Be it known that I, NICK W. KLINE, a citizen of the United States, residing at Los Angeles, in the county of Los Angeles and State of California, have invented new and useful Improvements in Trusses, of which the following is a specification.

This invention relates to a truss and particularly pertains to a truss for supporting 10 ruptures in the groin.

It is the object of this invention to provide a truss which can be worn with comfort and attached to the body of the wearer in such manner that it will remain in its 15 proper position irrespective of the position of the body and will permit freedom of movement without danger of being displaced, thus overcoming the principal objections to trusses now generally in use. Other 20 objects will appear hereinafter.

The invention is illustrated in the accompanying drawings, in which;

Figure 1 is a perspective view of the truss;

25 Fig. 2 is a view in cross section and elevation;

Fig. 3 is a detail in elevation of the truss-pad supporting plate;

More specifically 6 indicates a belt of 30 leather or other suitable material fitted with a fastening of any desired character and here shown as comprising a buckle 7.

A pad 8 is mounted on and covers the inner side of the belt and may be of any appropriate construction, this pad being attached to the belt by a few stitches or other fastenings 35 which will permit of its ready removal for cleansing.

Affixed to the belt on the front portion 40 thereof is a flexible metallic plate 9 having a pair of spaced inwardly curved dependent portions or ears 10 and 11 constituting a backing for truss pads 12 for supporting a rupture and which pads are preferably

45 formed as part of the belt pad 8. The ears 11 and 12 are thus inseparably and flexibly connected together and are spaced apart such distance as to dispose them in the proper position over the groin of the wearer to 50 cover and form a support for a rupture on either or both sides of the person.

A flexible lining 13 is placed over the inner face of the metallic plate and its ears and arranged between the plate and the

pads, rivets 14 passing through the belt, 55 plate and lining to secure these parts together.

Attached to the belt and extending over each of the ears is a pair of straps 15—16 and 17—18 preferably formed of silk. The 60 straps in each pair are arranged criss-cross fashion with their intersections connected together at the lower edge of the ear and with the edges of the portions extending over the ear stitched to the lining to cover 65 the edges of the ear. The outer divergent portions of the straps are designed to pass between the limbs of the wearer and to engage the limbs a short distance below the crotch. The straps of one pair are connected to one side of the belt and the straps of the other pair are connected to the other side of the belt, the pairs of straps thus 70 extending in opposite directions in relation to each other. The belt and straps are fitted 75 to the person so as to position the belt approximately over and in front of the hip joint so as to afford the person freedom of movement of the hips and back without disturbing the position of the belt and truss 80 pads, and without hampering such movement. The straps are positioned immediately below the protuberance of the buttocks and brought upwardly at the sides at an angle with their ends connecting with the 85 belt close to the hip joint and spaced apart. By this arrangement the straps are disposed clear of the crotch and therefore do not interfere with the evacuating functions and also are not liable to become soiled so that 90 they need not be detached or the truss removed when exercising such functions. Furthermore by not extending into the crotch they afford no discomfort to the wearer. By providing a pair of divergent 95 straps on each side the belt is securely held against displacement and freedom of movement of the limbs may be enjoyed.

Any suitable means may be employed for attaching the straps to the belt but they are 100 preferably permanently affixed thereto after fitting the truss to the person. When thus secured to the belt, the truss is put on by passing the limbs between the straps and belt with the belt unfastened and drawing 105 the truss upward into position. The belt is then fastened around the hips as before described and by reason of the arrangement of

the straps and their direction of pull on the belt the latter will be positioned below the kidneys.

In supporting a rupture it is desirable to 5 place a pad of cotton or the like over the rupture against which the dependent ear and its pad will bear, thus obviating the use of hard supports adjacent the body as is the present practice and thereby further 10 rendering the device comfortable to the wearer.

I claim:

1. In a truss, a belt, a flexible plate on the 15 front portion of said belt, a pair of spaced dependent ears on said plate, and a pair of straps affixed relative to each of said ears and diverging downwardly and rearwardly therefrom, said straps adapted to pass rearwardly between the limbs of the person with 20 the outer end portions of each pair of straps extending upwardly and outwardly in opposite directions and affixed to the opposed sides of the belt, the straps in each pair diverging from each other to their connection 25 with the belt.

2. In a truss, a belt, a pair of straps affixed

to the front portion of said belt on one side of the center thereof, a corresponding pair of straps secured to the front portion of the belt on the other side of the center thereof, 30 the straps in each pair crossed adjacent to their connection to the belt and secured together at their intersections, the outer portions of the straps of each pair diverging from their intersections, the end portions of one pair of the straps connected to one side of the belt and the end portions of the other pair of straps connected to the other side of the belt with the ends of the straps in 35 each pair spaced apart.

3. In a truss having a waist belt, a series 40 of four straps affixed to the front portion of said belt with a pair of the straps arranged on each side of the center thereof and with the straps of each pair intersecting and extending at an angle to each other to engage 45 the limb in spaced relation to each other, and means for connecting the spaced ends of each pair of straps to the side and rear portions of the belt.

NICK W. KLINE.
